US00D467179S

(12) **United States Design Patent** (10) Patent No.: **US D467,179 S**
 Nelson et al. (45) Date of Patent: **** Dec. 17, 2002**

(54) **BEVERAGE BOTTLE**

- (75) Inventors: **Brent S. Nelson**, Bradenton, FL (US);
Sheldon E. Yourist, York, PA (US)
- (73) Assignee: **Tropicana Products, Inc.**, Bradenton, IL (US)
- (**) Term: **14 Years**
- (21) Appl. No.: **29/143,029**
- (22) Filed: **Jun. 6, 2001**
- (51) LOC (7) Cl. **09-01**
- (52) U.S. Cl. **D9/503; D9/549**
- (58) Field of Search ..... D9/500, 502, 503, D9/516, 530, 537, 538, 539, 540, 542, 543, 549, 574, 575; 206/527; 215/200, 316, 329, 354, 382, 383, 384, 400; 220/200, 260, 288, 289, 890; 221/312 R
